[57] CLAIM

The ornamental design for a container for preserved seafoods, as shown and described.

DESCRIPTION

FIG. 1 is a top perspective view of a container for preserved seafoods showing our new design;

FIG. 2 is an exploded perspective view thereof;

FIG. 3 is a front elevational view of FIG. 1;

FIG. 4 is a side elevational view of FIG. 1, the undisclosed opposite sides being identical;

FIG. 5 is a top plan view of FIG. 1;

FIG. 6 is a bottom plan view of FIG. 1;

FIG. 7 is a top plan view of a second embodiment of the container as disclosed in FIG. 1;

FIG. 8 is a bottom plan view of FIG. 7;

FIG. 9 is a front elevational view of FIG. 7;

FIG. 10 is a side elevational view of FIG. 7, the undisclosed opposite sides being identical;

FIG. 11 is a top plan view of a third embodiment of the container as disclosed in FIG. 1;

FIG. 12 is a bottom plan view of FIG. 11;

FIG. 13 is a front elevational view of FIG. 11; and,

FIG. 14 is a side elevational view of FIG. 11, the undisclosed opposite sides being identical.
